UNITED STATES PATENT OFFICE.

EDWARD JACKSON YORK, OF HOUSTON, TEXAS, ASSIGNOR, BY DIRECT AND MESNE ASSIGNMENTS, OF ONE-THIRD TO WALTER L. HOWZE, OF HOUSTON, TEXAS, AND ONE-THIRD TO THOMAS W. CALDWELL, OF DUKE, TEXAS.

CATTLE-GUARD.

No. 891,127.

Specification of Letters Patent.

Patented June 16, 1908.

Application filed October 9, 1907. Serial No. 396,582.

To all whom it may concern:

Be it known that I, EDWARD JACKSON YORK, a citizen of the United States, and a resident of Houston, in the county of Harris 5 and State of Texas, have invented a new and useful Improvement in Cattle - Guards, of which the following is a full, clear, and exact description.

The purpose of the invention is to provide 10 a cattle guard of very simple, durable, and economic construction, that can be readily and quickly applied to any track, and which does not require in its application any extra timbers, ties, or excavation, and further- 15 more to so construct the cattle guard that it can be easily dismantled and replaced when the track is to be repaired.

It is the further purpose of the invention to provide a cattle guard that will not trap 20 stock since there is no footing for them, and wherein a smooth rolling surface is provided between and at the outer sides of the rails, practically flush with the tread of the rails, so that should stock fall thereon they will 25 not be injured, and may readily work themselves to one or the other side of the track.

The invention consists in the novel construction and combination of the several parts as will be hereinafter fully set forth 30 and pointed out in the claims.

Reference is to be had to the accompanying drawings forming a part of this specification, in which similar characters of reference indicate corresponding parts in all the figures.

Figure 1 is a plan view of the improved 35 guard applied to a track; Fig. 2 is a longitudinal section taken practically on the line 2-2 of Fig. 1; Fig. 3 is a transverse section taken substantially on the line 3-3 of Fig. 1; Fig. 4 is a sectional view of one of the rollers 40 employed; Fig. 5 is a perspective view of one of the end supporting plates of the structure; Fig. 6 is a perspective view of an intermediate side supporting plate; and Fig. 7 is a 45 perspective view of an intermediate supporting plate adapted to be located between the rails.

A and A' represent the rails of a track. The improved guard consists of a series of 50 supporting plates, longitudinal bars, and rollers carried by the bars. The end plates B are shown in detail in Fig. 5. Each end plate consists of a base member 11 adapted to rest upon a tie and to extend preferably

the length thereof at its upper face, and the 55 said base member 11 is provided at one longitudinal edge adjacent to its ends with horizontal extensions 12, and these extensions 12 are so located with respect to the end portions of the base member 11, that when the 60 base member of an end plate is on a tie and the rails are laid, the rails will rest upon the said extensions 12 and across the base member 11 adjacent to said extensions.

In the further construction of an end plate 65 B, an arched, upwardly extending flange 13 is formed at the same edge beyond which the extensions 12 are carried. This arched flange 13 extends from one extension to the other, and at the outer edge of each base extension 70 12 another flange is formed at the same edge of the base member 11, and said outer flanges are designated as 14 and are given an upward and inward inclination. In fact, the end flange 14 constitutes practically a con- 75 tinuation of the arch of the intermediate flange 13. When the rails are laid on the end plates B, the outer ends of the intermediate flanges 13 engage with the inner faces of the flanges of the rail, while the inner ends 80 of the end flanges 14 engage with the outer faces of the said rail flanges. The plate flange 13 is provided with a series of apertures 15 and the end flanges 14 are provided with apertures 15^a, as is shown in Fig. 5. 85

In addition to the end supporting plates B shown in Fig. 5, a series of intermediate supporting plates C is employed, adapted, however, to extend only from the inner face of one rail to the corresponding surface of the 90 opposing rail. The intermediate plates C may be termed bed plates, and each intermediate bed plate C, as is shown in Fig. 7, consists of a base member 16 adapted for attachment to the upper face of a tie, and an 95 upwardly arched flange 17 that extends by preference beyond the end portions of the base member 16, and the flange 17 of the bed plate C corresponds to the flange 13 of the end plate B; and each flange 17 of an intermediate bed plate C is provided with a series of apertures 18, corresponding in number and in location to the apertures 15 in the flanges 13 of the end plates. In connection with each bed plate C, an outer or supporting 100 plate D is employed which is shown in detail in Fig. 6. These end supporting plates D consist of an angular base section comprising

a transverse member 19 and a longitudinal member 20, both of which members are adapted to be secured to the upper face of a tie adjacent to the outer faces of the rails, 5 and the transverse member 20 of each end supporting plate D is placed beneath a rail and corresponds to an extension 12 from an end plate B. An upwardly extending flange 21 is carried from the longitudinal edge of the 10 longitudinal member 19 of each of the end supporting plates D, and these flanges 21 are given an upward and inward inclination and correspond to the flanges 14 on the end plates B, and the flanges 21 are provided with apertures 22 corresponding to those in the aforesaid flanges 14. I desire it to be understood, however, that if desired all of the supporting plates may be constructed as is shown in Fig. 5, but the construction shown is preferred since it admits a more ready assemblage of the parts and a more expeditious removal when the track is to be repaired.

Rods 23 are arranged in parallelism between the rails A and A', and these rods are 25 passed through corresponding apertures in the flange portions of the supporting plates located between such rails, and at the ends of the structure approaching plates 24 and 24^a are located, the plates 24 being between 30 the rails and the plates 24^a at the outside portions of the rails, and these approaching plates extend upward from the road bed to the upper edges of the flanges 13 of the end plates B, as is illustrated in Fig. 3, and each 35 of the said approaching plates at its upper edge, or where it engages with an end plate B, is provided with a downwardly extending flange 25, as shown in Fig. 2, bearing against the outer faces of the end plates, and sundry 40 of the rods 23 are passed through the flanges 25 and these rods are provided with nuts at both of their ends, but the other rods 23 are provided each with a head at one end, and a nut at the opposite end. Similar rods 45 26 are passed through the apertures in the outer flanges 14 of the end plates and the flanges 21 of the intermediate end plates, and these rods 26 are likewise carried through the approaching plates 24^a.

50 Each rod 23 and 26 is provided with a series of rollers E loosely mounted. These rollers are arranged in staggered order, that is to say the rollers on adjacent rods alternate, as is illustrated in Fig. 1. The rollers 55 E are preferably made hollow and of light steel, or other suitable material, and their peripheral surface 27 is flat but their side sections 28 are oval so that should a rod break on a train and trail over the rollers, 60 there is little liability of the free end of such rod becoming entangled with, or being held between the rollers. The rollers E that are

mounted on the side rods 26 are graduated in size, the largest form of roller which is of the same diameter as those between the rails, 65 being located adjacent to the rails, while those rollers that are furthest removed from the rails are of the smallest diameter, as is clearly shown in Fig. 2, and the rollers between the rails are also preferably graduated in size. It will be understood that in the formation of the guard it is arched between the rails and that its upper face is nearly flush with the tread of the rails, and that the guards at the sides of the rails have 75 more or less of a downward and outward inclination at their upper surfaces.

It is evident that a cattle guard of the type described may be quickly, conveniently, and economically erected and as readily dismantled when necessary, and that the rolling surface it presents is such as to prevent animals obtaining any foot-hold, and if by any possibility an animal should fall upon the surface of the guard, it is an easy matter for 85 such animal to work itself to either one side or the other of the track.

Having thus described my invention, I claim as new and desire to secure by Letters Patent, —

1. A cattle guard consisting of a bed constructed of a series of transverse plates, rods passed longitudinally through said plates, said rods being in parallelism, and rollers having oval sides mounted on the said rods 95 the rollers of one rod alternating with the rollers of the adjacent rods and being in contact therewith, the said bed being divided into a central and outer sections, having spaces between them for the reception of the 100 rails of a track, and members upon which the said rails rest.

2. A cattle guard for railway tracks, consisting of a body composed of a series of parallel transverse plates, a series of longitudinal 105 rods arranged in parallelism and passed through said plates, and rollers having oval sides loosely mounted on the said rods, the rollers on adjacent rods being in alternate relation to each other and in contact, the 110 said bed being divided into a central section and outer sections, separated from each other by spaces for the passage of the rails of the track, and tie sections for sundry of the plates that are adapted to engage with 115 the under faces of the rails of the track said guard being arched transversely of the track.

In testimony whereof I have signed my name to this specification in the presence of two subscribing witnesses.

EDWARD JACKSON YORK.
